FREIGHT BRACING APPARATUS

Fred B. Miller, Livonia, Mich., assignor to Evans Products Company, Plymouth, Mich., a corporation of Delaware

Filed Aug. 15, 1961, Ser. No. 131,624

5 Claims. (Cl. 105—369)

The present invention relates to freight bracing apparatus and more particularly to apparatus for use in vehicles such as boxcars or trucks having belt rails mounted on opposite sides thereof and extending longitudinally therealong and crossbars extending transversely of the vehicle and connected at its opposite ends to the belt rails.

More particularly the present invention relates to an improved freight bracing apparatus of the type shown in the copending application of Henry L. Dunlap, Serial Number 836,168, filed August 26, 1959, now Patent Number 3,071,086. In some conditions of use of the apparatus there shown it has been found that the end fitting will be accidentally disconnected from the belt rail. Also, it has been found that the end fittings have not always remained properly connected to the belt rail sections which are carried on the doorway members which are mounted in and extend across doorway openings.

Accordingly, it is an object of the present invention to provide an improved cross member end fitting cooperable with the belt rail members to provide an improved connection thereto which overcomes these defects.

It is also an object of the present invention to provide an improved end fitting having an improved mounting for the latch which more accurately locates it and facilitates better engagement with the belt rail.

Another object of the invention is to provide an improved end fitting construction having improved means for transferring loads on the pins longitudinally of the belt rails to the end fitting body member.

Other and more detailed objects of the present invention will be appreciated by those skilled in the art from a consideration of the following specification, the appended claims and the accompanying drawings wherein:

FIGURE 1 is a broken plan view of freight bracing apparatus embodying the present invention and showing to some extent diagrammatically, a crossbar extending between belt rails secured to opposite sidewalls of a railway boxcar;

FIGURE 2 is a broken enlarged sectional view of the structure illustrated in FIGURE 1 taken substantially along line 2—2 thereof showing the connection of the end fitting to a fixed belt rail disposed in a normal vertical position;

FIGURE 3 is a broken sectional view similar to FIGURE 2 but showing the connection of the end fitting to a belt rail carried on a doorway member which has been rotated through a small angle so that the belt rail is inclined to the vertical;

FIGURE 4 is a broken side elevational view of the left hand end fitting as viewed in FIGURE 1;

FIGURE 5 is an end view of the end fitting illustrated in FIGURE 4 looking in the direction of the arrow 5 and showing a broken section of belt rail in broken lines; and

FIGURE 6 is a broken plan view of the end fitting illustrated in FIGURE 4.

While it will be readily appreciated by those skilled in the art that the improvements of the present invention may be readily incorporated in freight bracing apparatus of widely differing types and sizes having numerous applications, the improvements of the present invention are herein illustrated and described as embodied in apparatus for supporting and bracing general merchandise in railroad boxcars.

2

Referring to the drawings, the railroad boxcar sidewalls are diagrammatically represented at 10 and 12 and carry belt rails 14 which are of the construction shown and described in greater detail in the above-mentioned copending application. As there disclosed the sidewalls carry a plurality of belt rails disposed in vertically spaced parallel relation and extending horizontally therealong. The belt rails on opposite sidewalls 10 and 12 are disposed at corresponding levels so that a crossbar 16 extending therebetween will be disposed horizontally. In accordance with conventional practice the crossbar 16 includes a fixed end fitting 18 illustrated at the left end of the cross bar 16 as viewed in FIGURE 1 and a telescopic end fitting 20 at the right end of the crossbar as there viewed. The connection of these end fittings 18 and 20 to the crossbar body 22 as well as the construction of the latter form no part of the present invention and may be of any suitable construction such for example as that disclosed in the above-mentioned application.

10 The belt rails 14 are of the same construction disclosed in the above-mentioned application and include an upwardly extending support flange 24 having a support surface 26 at its upper edge. The belt rail 14 also has a lower portion 28 coplanar with the flange 24 and having a plurality of apertures 30 uniformly spaced therealong. The belt rails 14 are welded to the side walls with the flange 24 and portion 28 extending vertically.

15 The end fittings 18 and 20, except for the portions thereof providing the fixed and telescopic connection respectively with the bar body 22, are identical in construction and accordingly only one need be described. Each end fitting includes a body member 32 the outer end portion of which is yoke-shaped with horizontally spaced arms 34. Extending across the tops of the arms 34 is a cap 36 which is welded to the body member 32 and has an opening 37 extending vertically therethrough. As best illustrated in FIGURE 2 the cap 36 extends outwardly beyond the ends of the yoke arms 34 and includes a downwardly facing support surface 38 adapted to engage the belt rail supporting surface 26 to support the end fitting thereon and a depending hook 40 adapted to extend between the flange 24 and the sidewall to hold the end fitting against pulling away from the sidewall in a direction at right angles thereto.

20 Each end fitting also includes a latch 42 which is mounted within the opening 37 of the cap 36 and extends downwardly between the yoke arms 34. The upper portion of the latch 42 includes a pair of projecting ears 44 having aligned apertures 46 therethrough receiving a pivot pin 48 which is mounted in and extends transversely of the cap 36. The fit of the apertures 46 on the pivot pin 48 is such that the latch 42 is freely slideable longitudinally of the pin 48. In spaced relation below the mounting projections 44 the latch 42 carries a pair of spaced parallel latch pins 50 adapted to project into selected ones of the apertures 30 in the belt rail 14 and when so disposed to be engageable with the belt rail 14 around the periphery of the apertures 30 to both hold the end fitting against movement longitudinally of the belt rail 14 and to hold the end fitting against upward movement relative to the belt rail as is necessary to move the hook 40 of the cap 36 from between the belt rail flange 24 and the adjacent side wall. Intermediate the latch pins 50 and the mounting projections 44 a leaf spring 52 acts between the latch 42 and the body member 32 to urge the latch 42 in a clockwise direction about the pivot pin 48 as viewed in FIGURE 2. In the preferred construction illustrated one end of the spring 52 is riveted to the latch 42 and the other end bears against the end fitting body member 32 between the yoke arms 34.

25 At the lower portion of the latch 42 and extending

generally in the opposite direction from the latch pins 50 is a projection 54 adapted to the engaged by a worker for pivoting the latch 42 in a counterclockwise direction about the pivot pin 48, as viewed in FIGURE 2, against the action of the spring 52. The latch 42 may thus be moved by the worker to the retracted position illustrated in broken lines in FIGURE 4. It will be noted that in this retracted position the outer ends of the latch pins 50 do not extend beyond the plane there indicated by the line A and which is defined by the lower outer end portions of the yoke arms 34. When the end fitting is connected to a belt rail disposed in the normal position mentioned above with the flange 24 and portion 28 extending vertically as shown in FIGURE 2, the latch 42 is disposed in its normal operative position in which it will be noted that the latch pins 50 extend horizontally through the apertures 30. The latch is provided with flat annular shoulder surfaces 56 (see FIGURE 5) which are held against the adjacent surface of the belt rail portion 28 by the latch spring 52.

FIGURE 3 illustrates the connection of the end fitting to a belt rail 14 carried by a doorway member which is there fragmentarily illustrated at 57. The use of doorway members to support belt rail sections of various shapes is well known and the doorway member 57 may be of any suitable construction. Because these doorway members must be removable to enable loading and unloading of the boxcar they cannot be welded in fixed position. The mountings of these doorway members because of necessary tolerances and because of wear in use allow for some limited rotary movement of the doorway member from its normal position in which the belt rail flange 24 and portion 28 extend vertically, to for example the position illustrated in FIGURE 3 in which the flange 24 and portion 28 are inclined relative to the vertical. Referring to FIGURE 3, it will be noted that when the end fitting is connected to a belt rail disposed as there illustrated the latch 42 is disposed with the latch pins 50 extending slightly upwardly and with the annular shoulder surfaces 56 parallel to and fully engaging the belt rail portion 28 in the same manner as in the normal operative position illustrated in FIGURE 2.

Movement of the latch in a clockwise direction beyond its normal operative position best illustrated in FIGURES 2 and 4 is limited by cooperating stops 58 and 60 provided on the latch 42 and on the inner sides of the yoke arms 34. The spacing between these stops in the normal operative position is clearly illustrated in FIGURES 4 and 6. The limiting position in which these stops are engaged is illustrated in FIGURE 3. This may also be referred to as the free position of the latch since it is the position to which the spring 52 urges the latch 42 when it is not connected to a belt rail.

The latch 42, as best illustrated in FIGURE 5, is provided on opposite sides thereof, adjacent the pins 50 with flats 62 which extend at the same angle as the draft angle on the lower portion of the inner surface of the yoke arm 34. This surface is indicated at 64 in FIGURE 5. These flats 62 and the yoke arm surfaces 64 constitute cooperating abutments through which loads on the latch pins 50 in either direction along the axis of the pivot pin 48 will be directly transmitted through these abutments to the yoke arm 34 of the end fitting body member 32, the fit of the latch projection apertures 46 on the pivot pin 48 being, as stated heretofore, such that the latch moves freely along the pivot pin until the abutments 62 and 64 engage.

While only one specific embodiment of the present invention has been illustrated and described in detail herein it will be readily appreciated by those skilled in the art that numerous modifications and changes may be made without departing from the scope of the present invention.

What is claimed is:

1. In an apparatus for supporting and bracing general merchandise in freight cars and the like, a crossbar end fitting comprising a body member having means at one

side thereof for connecting said end fitting to an associated crossbar, said body member including a yoke portion having spaced arms extending in opposed relation to said means and a cap overlying and secured to the top of said yoke portion and defining an opening extending transversely of said body member and communicating with the space between said arms, said cap extending beyond the outer end of said arms of said yoke portion and including a hook portion including a support surface for supporting said end fitting on an associated support member and having an anti-pullaway surface extending substantially at right angles to said support surface for engaging behind a part of said associated support member to prevent said end fitting from pulling away therefrom, a latch member disposed within said opening and between said arms of the yoke portion of said body member and having a latch pin extending in generally opposed relation to said connecting means, means mounting said latch member on said body member for movement relative thereto between a retracted inoperative position a normal operative position in which the axis of said latch pin is disposed parallel to said support surface for engaging said support member when the latter is in its normal position and a fully extended position disposed beyond said normal operative position in a direction away from said retracted position, and means engaging said latch member and urging it toward said fully extended position.

2. A crossbar end fitting as defined in claim 1 including pin means mounting said latch on said end fitting between said arms of said yoke portion and for free sliding movement longitudinally of said pin means, co-operating abutment surfaces on said latch adjacent said latch pin and on said arms of said yoke portion for limiting movement of said latch longitudinally of said pin means whereby loads applied to said latch through said latch pin are directly transmitted through said abutment surfaces to said spaced arms of said yoke portion of said body member.

3. A crossbar end fitting as defined in claim 1 for connecting one end of a freight bracing crossbar to an associated support member as recited in claim 1 which associated support member includes a flange providing said support surface and said anti-pullaway surface and includes a spaced portion coplanar with said flange and having latch apertures therethrough and wherein said latch has a shoulder adjacent said latch pin adapted to engage said spaced portion of said associated support member adjacent one of said apertures therein and including means urging said latch in a direction away from said retracted position and co-operating stop means on said latch adjacent said latch pin and on said spaced arms of said yoke portion preventing movement of said latch in said direction beyond said fully extended position.

4. A crossbar end fitting for connecting one end of a freight bracing crossbar to an associated supporting belt rail having a support flange including a support surface and an anti-pullaway surface and a coplanar spaced portion having latch apertures therethrough, the belt rail being mounted for limited rotary movement to and from a normal position in which said flange and said spaced portion are disposed vertically, said end fitting comprising means at one end for connecting said end fitting to said crossbar and means at the other end for connecting said end fitting to said belt rail, said last named means comprising a hook on said end fitting adapted to hook over said belt rail flange for engaging said support surface and said anti-pullaway surface and including a hook support surface adapted to engage said support surface of said flange, a latch having at least one latch pin adapted to selectively extend into the apertures of said belt rail for holding said hook hooked over said belt rail flange, and means mounting said latch on said end fitting for pivotal movement to and from a retracted position and for pivotal movement between said retracted position, a normal operative position in which said latch pin extends parallel

to said hook support surface and a fully extended position disposed beyond said normal operative position in a direction away from said retracted position whereby said latch pin may extend through said aperture at right angles to said spaced portion of said belt rail in all positions of said belt rail throughout said limited rotary movement thereof.

5. The combination defined in claim 4 wherein said latch has a surface adjacent said latch pin extending at right angles thereto adapted to engage said spaced portion of said belt rail, cooperating stops on said latch and on said end fitting adapted to engage each other to stop said latch upon movement thereof beyond said normal operative position in a direction away from said retracted posi-

tion when said latch reaches a fully extended position, and means urging said latch toward said fully extended position.
